UNITED STATES PATENT OFFICE.

GEORGE B. JONES, OF KOKOMO, INDIANA, ASSIGNOR TO THE GLOBE STOVE & RANGE CO.,
OF KOKOMO, INDIANA.

STOVE-DOOR AND PARTICULARLY OVEN-DOOR FOR STOVES.

1,260,776.

Specification of Letters Patent. Patented Mar. 26, 1918.

Application filed November 1, 1915. Serial No. 59,127.

To all whom it may concern:

Be it known that I, GEORGE B. JONES, a citizen of the United States, residing at Kokomo, county of Howard, State of Indiana, have invented certain new and useful Improvements in Stove-Doors and Particularly Oven-Doors for Stoves, of which the following is a specification.

This invention relates to stove doors and 10 particularly to oven doors for stoves.

The object of the invention is to provide a simple and effective means of supporting the sheet metal back plate on the cast frame.

Further objects, and objects relating to 15 details and economics of construction and manufacture will definitely appear from the detailed description to follow.

I accomplish the objects of my invention by the devices and means described in the 20 following specification. The invention is clearly defined and pointed out in the claims.

A structure which is a preferred embodiment of my invention is clearly illustrated in the accompanying drawing, forming a 25 part of this specification, in which:

Figure 1 is a perspective view of the rear of a stove door embodying my invention, with the lower half of the back plate broken away.

Fig. 2 is an enlarged perspective view of the corner of the pattern which is used for making the front frame of the door.

Fig. 3 is a perspective view of the tin duff used.

Fig. 4 is another perspective view of this tin duff, showing it in a different position.

Fig. 5 is a perspective view of one corner of the back plate.

Fig. 6 is a section on the line 6—6 of 40 Fig. 1.

Fig. 7 is a fragmentary view through the mold used in casting the front frame, showing the location of the tin duff.

In the drawing similar reference characters refer to similar parts throughout the 45 several views, and the sectional views are taken looking in the direction of the little arrows at the ends of the section lines.

Referring to the drawing, the door comprises a front frame 10 which is rectangular and is provided with rearwardly projecting inner and outer flanges 11 and 12 respectively, bordering the sides and the top of the frame. The shape of this frame will 50 vary, of course, with different stove designs.

This front frame is of cast metal. On the inner face of the outer flange 11 are a number of lugs 13, which are cast with the frame, and at each corner of this outer flange 11 is a triangular inwardly projecting flange 14. A back plate 15, of sheet metal, rests against the rear edge of the inner flange 12 and on the ends of the lugs 13, and is provided with corners 16 which are displaced slightly out of the plane of the body of such back plate 15 so as to extend under the corner flanges 14. These flanges thus serve to hold the back plate firmly against the front plate. The only additional fastenings necessary to hold the back 60 plate 15 in place are a small number of screws 17, which extend through this back plate into internally threaded circular lugs 18 projecting from the rear face of the cast frame 10, and these lugs are the only parts 65 which require machining. The corner flanges 14 coating with the centrally disposed screws 17 make fastening at points other than centrally at each side unnecessary, and the door is very effective with but 70 a single screw at each side. In the usual construction many screws are required. Because each side is provided with but a single point of fastening, there is no warping of the structure because the sheet is free 75 to expand and contract.

The flanges 14 are preferably formed by the use of tin duffs, which both make the flanges stronger and facilitate their manufacture. In the use of these tin duffs, the 80 pattern 20 for the cast frame 10 has an outer flange 21 corresponding to the flange 11 of the frame, and set in the corners formed by the flange 21 is a fillet 22 which extends less than the full height of such 85 flange and is provided on its upper surface with a projecting pin 22', conveniently formed by driving a headless tack into the fillet 22. When the frame is placed in the lower part 23 of the mold and sand 24 90 placed around it, and this lower part of the mold 23 has been inverted with the pattern within it, the open or concave part of the pattern is uppermost, bringing the pins 22' 95 at the various corners also uppermost. Then a tin duff 25 is placed on each fillet 24, these tin duffs being of the shape shown in Figs. 3 and 4 and provided with a hole 26 for fitting over the projecting pins 22'. The tin duffs 25 extend inward from the 100 105 110

corners beyond the edge of the fillet 22, and are of a general triangular shape, being provided along the hypotenuse of this triangle with a down-turned flange 27 which at its 5 lower edge is provided with an inwardly turned flange 28 which extends parallel to the body of the tin duff backward toward the fillet 22. After the tin duffs are in place, the upper part or cope 29 of the flask 10 is placed on the part 23 thereof, and is filled with sand 30, which sand 30 projects downward into the concave part of the pattern 20 and beneath the tin duff 25. The upper part of the flask is now removed 15 from the lower part, carrying the sand 24 and the tin duff 25 with it; then the pattern is removed, the two parts of the mold placed together again, and the metal poured into the flask in the usual manner. This 20 metal forms the frame 10 of the stove door, flowing around the edge of each tin duff and against part of its surface and through the hole 26 so as to make the tin duff an integral part of the frame.

Having thus described my invention, what I claim as new and desire to secure by Letters Patent, is:

1. A stove door, comprising a cast metal frame which has inner and outer rearwardly 30 projecting flanges and other flanges which project inwardly from the corners formed by the outer flange, a flat back plate of sheet metal which fits against the back of the cast frame by resting against the rear edge of 35 the inner flange and corners which extend under said corner flanges of the frame, and means for rigidly fastening intermediate portions of said back plate to said frame.

2. A stove door, comprising a cast metal 40 frame which has an outer rearwardly pro-

jecting flange and other flanges which project inwardly from the corners formed by the outer flange, a flat back plate of sheet metal which fits against the back of the cast frame and corners which extend under said corner flanges of the frame, and means for rigidly fastening intermediate portions of 45 said back plate to said frame.

3. A stove door, comprising a cast metal frame which has an outer rearwardly projecting flange and other flanges which project inwardly from the corners formed by the outer flange, a flat back plate of sheet metal which fits against the back of the cast frame and corners which extend under said 50 corner flanges of the frame, and means for rigidly fastening the said plate at a single point toward each side and end.

4. A stove door, comprising a cast metal frame having an outer rearwardly projecting flange and an inner rearwardly projecting flange, fillets in the corners of said rearwardly projecting flange spaced from the front of said frame, and a metal back plate resting on said inner flange and having its 55 corners inserted between said fillet and the front of the frame.

5. A stove door, comprising a polygonal cast metal frame having an outer rearwardly projecting flange, and fillets in the corners of said flange and integral therewith, the said fillets being spaced from the front of said frame.

In witness whereof, I have hereunto set my hand and seal in the presence of two 75 witnesses.

GEORGE B. JONES. [l.s.]
